(57) **CLAIM**

The ornamental design for a display screen with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of an embodiment of a display screen with graphical user interface of my new design.

FIG. 2 is a front view of a second image thereof.

FIG. 3 is a front view of a first image of a second embodiment; and,

FIG. 4 is a front view of a second image thereof.

The appearance of the transitional image sequentially transitions between the images shown in FIGS. 1-2 and FIGS. 3-4. The process or period in which one image transitions to another image forms no part of the claimed design.

The portions colored in blue form no part of the claimed design.

The outermost broken lines in the figures show a display screen or portion thereof, and form no part of the claimed design.

The any text and/or terms are shown in broken lines in the figures and depict environmental subject matter only and form no part of the claimed design.

The other broken lines in the figures show portions of the graphical user interface that form no part of the claimed design.
